POWER-DRIVEN WRITING MACHINE

Oscar J. Sundstrand, Bridgeport, Conn., assignor
to Underwood Elliott Fisher Company, New
York, N. Y., a corporation of Delaware

Application December 5, 1936, Serial No. 114,416

47 Claims. (Cl. 197—17)

This invention relates to power-driven writing machines.

Certain important objects of the invention are to improve the construction and mode of operation of the mechanism of typewriting machines for operating the type bars or corresponding elements by power.

Another object of the invention is to produce a mechanism for actuating the type bars of a typewriting machine by power in which mechanically applied power is transmitted to the driven element in a manner as nearly simulating a manual key operation as is possible.

Still another object of the invention is to provide a mechanism for operating the type bars of a typewriting machine by power which is particularly adapted for use on a flat platen machine of the Elliott Fisher type in which the type are projected downwardly upon the work sheets lying in a substantially horizontal position on the platen.

To these and other ends, the invention consists in certain novel features and combinations of parts, all of which will be more fully described hereinafter, and particularly pointed out in the claims.

In the accompanying drawings

Fig. 1 is a perspective view of a flatbed typewriting machine equipped with one embodiment of the invention;

Fig. 2 is a side view of the same;

Fig. 3 is an enlarged detail side view of a type bar action and key in normal position;

Fig. 4 is a similar view showing the parts in their operated positions, at the point of disengagement of the type bar action from the power-actuated driving element;

Fig. 5 is a fragmentary detail view in side elevation, showing the positions of the type bar action and key at the instant when the type bar action is engaged with the power-actuated driving element;

Fig. 6 is a similar view, showing the positions of the parts at the end of a printing operation, when the key has been held depressed;

Fig. 7 is a fragmentary perspective view, showing the pawl, which co-acts with the driving element, in its normal position relatively to its thrust link or pawl carrier;

Fig. 8 is a similar view showing the position of the pawl when transmitting motion from the driving element to the type bar action;

Fig. 9 is a detail top plan view, partly broken away, showing the type bar interlocking mechanism, one of the keys having been depressed;

Fig. 10 is a similar view, two keys having been simultaneously depressed to equal extents;

Fig. 11 is a detail sectional view in side elevation, showing the control of the usual escapement mechanism by the letter space bar;

Fig. 12 is a fragmentary rear perspective showing the power transmission from the motor to the drive member for the type bar action;

Fig. 13 is a detail perspective view of the bed for the rod on which the radius arms are fulcrumed, and

Fig. 14 is a detail horizontal sectional view of the traveling pulley forming part of the power transmission.

The invention is applicable to writing machines of both the round and flat platen types, but is conveniently illustrated as applied to the well-known Elliott-Fisher flatbed typewriting machine wherein the platen 10 is mounted between a pair of parallel rails 11, having suitable cross braces, one of which is shown at 12.

A hollow rectangular line spacing carriage 13 extends between the parallel rails 11 on which it is mounted for back and forth travel over the platen 10, the front and rear bars 14 of the line space carriage forming tracks for a traveling key carriage 15 equipped with front and rear wheels 16 resting on the tracks.

The key carriage 15 is arranged to travel across the platen from side to side in letter spacing direction and return.

A spring drum 17, (Fig. 1), urges the key carriage in letter spacing direction, the carriage being fed step by step by an escapement indicated at 33, (Figs. 3 and 11), of the type shown in Patent 1,203,519, under control of the manually operable keys 18 arranged in banks in the usual manner on the key carriage.

Reference is made to U. S. patents to Foothorap, No. 1,203,519, October 31, 1916, directed to the letter spacing feature; No. 1,251,361, December 25, 1917, showing the type action, partly utilized in the present invention; and No. 1,904,127, April 18, 1933, showing a motorized key carriage and line space frame.

The key carriage 15 is provided with a ribbon mechanism, column tabulating mechanism, line finder and other equipment, customarily applied to typewriting machines.

Power drive

Power from a motor 100, (Figs. 1, 2 and 12), similar to that shown in U. S. Letters Patent to Foothorap, 1,904,127, heretofore referred to, is utilized to return the key carriage 15 towards

the beginning of a line, and to shift the line spacing frame 13 and key carriage towards and from the operator in line spacing direction.

As in the prior patent just referred to, the motor 100 is supported on a bracket 101 secured to the rear rail 14 of the line spacing frame.

A worm 102 on the armature shaft 103 of the motor meshes with a worm wheel 104 normally clutched to a counter-shaft 105 journaled in the bracket structure 101. A gear 106 on the counter-shaft 105 meshes with a second gear 108 on a stub shaft 109 journaled in the bracket structure 101 and lying parallel with and below the counter-shaft 105.

For the purposes of the present invention which has no direct bearing on the motor-driven key carriage return, or the power driven line space frame, it may be understood that a bevel gear 110 near the forward end of the stub shaft 109 is in mesh with a second bevel gear 111 fast on a drive shaft 112 extending across the line space frame 13 and suitably journaled in brackets 113 projecting upwardly from the rear ends of the side bars of the line space frame.

Unlike the arrangement disclosed in Patent No. 1,904,127, the present motor is directly connected with a suitable source of power through a main switch 114, (Fig. 2), (like that numbered 209, Figs. 29 and 30 of Patent No. 1,904,127), to run constantly as long as the main switch is closed.

The left hand end of the drive shaft 112 is projected some distance beyond the left hand bracket 113 and supports a drive pulley 115 fast near its outer end. A belt 116 connects the pulley 115 with a second pulley 117 fast on the outer end of a non-cylindrical jack shaft 118 lying parallel with the drive shaft 112.

The outer end of the jack shaft 118 is journaled in the laterally turned ear 119 of a brace 120 projecting outwardly from the adjacent bracket 113, a spacing piece 121 extending rearwardly from the brace 120 and having a bearing 122 in which the projecting outer end of the drive shaft 112 is steadied, to prevent vibration.

The jack shaft 118 extends some distance across the space between the rails 11, its inner or right hand end being journaled in a bearing 123 carried at the forward end of a hanger 124, (Fig. 3), fastened at its rear end to the rear line space frame track bar 14.

A vertically-arranged sub-frame 125 (Figs. 1, 2 and 12) fastened to the left side of the key carriage 15 to travel therewith, carries at its lower end a laterally projecting tubular bearing 126 on which a traveling pulley wheel 127 is rotatably supported. (See Fig. 14.) A collar 135a having a non-circular bore to slidingly fit over the non-cylindrical jack shaft 118 is fast with the pulley 127 to enable the shaft to rotate the pulley. The shaft passes through the tubular bearing to its hanger 124, as above explained.

A belt 128 connects the traveling pulley 127 with a pulley 129 fast on the projecting left hand end of a fluted or toothed shaft or drive member 130 journaled in the side brackets 26, mounted on and extending upwardly from the cover plate 22 extending between the side frames 60 and closing the upper end of the key carriage.

An idler 131 is journaled in an idler frame 132 pivotally supported on a stud 133 mounted on the sub-frame 125 and having a head 134 of irregular shape to extend over the outer or left hand end of the traveling pulley 127, a spring 135 operating to press the idler against one 75

course of the belt 128 to maintain the belt taut.

The head 134 of the stud 133 extends over the outer end of the traveling pulley 127 and, by the engagement of the head of the stud and the lower end of the sub-frame 125 with the opposite ends of the traveling pulley, the pulley is shifted along the jack shaft 118 during the movements of the key carriage, the head preventing the traveling pulley from slipping off the bearing 126.

The leftward extensions of drive shaft 112 and the jack shaft 118 are provided because of the extent of travel of the key carriage 15. When the key carriage is at the beginning of a line 15 at its limit of leftward travel, the traveling pulley 127 is near the left hand drive pulley 117. The traveling pulley 127 accompanies the key carriage as the latter travels in letter spacing direction, and return, due to its confinement between the 20 sub-frame 125 and the head 134 of the stud 133.

So also, the jack shaft 118 extends to the right a sufficient distance to enable the traveling pulley 127 to accompany the key carriage 15 to its limit of movement in such direction.

Obviously, energization of the motor 100 will cause the transmission of power through the armature shaft 103, worm 102, worm wheel 104, counter shaft 105, transmission gears 106, 108, stub shaft 109 and bevel gears 110, 111 to rotate the drive shaft 112 and drive pulley 115, the belt 116 transmitting rotation to the jack shaft 118, through the fast pulley 117 on the latter shaft.

And rotation of the jack shaft 118 will be transmitted through the travelling pulley 127, belt 128, and pulley 129 to the fluted or toothed drive member 130.

The drive member 130, in turn, imparts a power stroke to the type bar actions, as follows:

Key action

This portion of the invention is illustrated as applied to the down-strike key action of the well-known Elliott-Fisher machine, as shown in Foothorap patent, No. 1,251,361, hereinbefore referred to. As much of the patented structure as possible has been retained to reduce the expense of converting the former manually operable key actions into power-driven key actions.

However, much of the type bar linkage disclosed in the above-named patent would be eliminated in other styles of machines.

The Elliott-Fisher key carriage 15 is provided with a horizontally arranged deck 41 located beneath the keyboard, a semi-circular type bar ring 42 being suspended by struts 43 some distance below the deck, and just above the platen 10, the superposed deck being recessed at its forward edge in substantial register with the type bar ring.

A series of type bar hangers 44 are secured alternately to the upper and lower faces of the type bar ring 42, all as shown in Patent No. 1,251,361, type bars 45 being pivotally secured near one end at 46 to the respective hangers, the opposite free ends of which type bars carry types 47.

Suitably anchored retracting springs 48 connected at their lower ends with the respective type bars 45 yieldingly retain the type bars in, and return them to, their normal vertical positions wherein the free ends of the bars contact a semi-circular buffer ring 49 mounted above the level of the deck 41 on posts 50 projecting upwardly from the type ring 42 through the semi-circular recess formed in the front edge of the deck.

Turn buckle links 51 connect the tails of the respective type bars 45 with elbow levers 52 individual thereto and journaled in bifurcated hangers 53 depending from the deck 41.

Links 54 connect the elbow levers 52 below the deck 41 with the forward ends of sub-levers 55, each of which is pivoted on its individual fulcrum stud supported on a bracket 56 projecting upwardly from the deck and arranged for rotary adjustment to enable the sub-levers to be correctly positioned to transmit motion from the parallel horizontally arranged intermediate levers 58 to their respective type bars 45 arranged in a semi-circle around the type bar ring 42.

Push rods 57 connect the rear ends of the sub-levers 55 with the parallel intermediate levers 58 extending from front to rear of the key carriage, the rear ends of the intermediate levers being journaled on a fulcrum bar 59 extending across the rear of the key carriage and suitably supported at its ends in the opposite side frames 60 of the key carriage.

Springs 61 connected to the intermediate levers 58 near their fulcrums assist the retracting springs 48 in yieldingly holding their respective intermediate levers 58 and the thereto-connected linkages in their normal positions.

The forward ends of the intermediate levers 58 project through slots 62 in the front wall of the key carriage casing, the upper edges of such forward ends being faced to contact a cushioning and noise-deadening bar 64 of suitable material seated in a channel 65 formed by flanging the upper edge of the front wall.

The type bar linkage, as thus far described, corresponds with the disclosure in the above-mentioned Foothorap patent, No. 1,251,361, it being quite evident that the intermediate levers 58 are very like the manually operated key levers of the said patent, but cut off at a point just in front of the front wall of the key carriage casing.

Power-driven type bar action

The present invention relates particularly to improvements in Power-driven key or type bar actions, of the class embracing the U. S. patents to Schlüns, Nos. 1,199,824, October 3, 1916; 1,579,151, March 30, 1926; and to Schulze 1,789-661, January 20, 1931, wherein the former, manually operable key action constituting a connected train of linkage from the key lever to the type bar, is interrupted or formed of independently operable sections, one of which is a power-driven type bar action, and the other of which is a manually operable key lever, pressure on which shifts the type bar action into engagement with the continuously actuated driving element 130.

In the present invention, each of the keys 18 in each bank is mounted on the outer end of a key lever 19, (Figs. 3-6), journaled at its inner end on a shaft 20 common to the keys of all banks. The ends of the key lever shaft 20 are mounted in the side frames 60 of the key carriage.

The particular key illustrated in Figs. 3 and 4, for instance, is one in the lowest bank of keys, the forwardly extending arms of the key levers of the respectively higher banks, being successively shorter than the forwardly extending arms of the lowest bank to thus provide a stepped keyboard. The forwardly extending arms of the key levers 19 project through guide slots 21 formed in the depending flange at the forward edge of the cover plate 22.

To maintain the dip of the keys of all the banks uniform, each key lever 19 is provided at its inner end with a vertically extending arm 19^a, all of which arms are of equal length, and extend through guide slots 23 formed in the horizontal face of the cover plate, the upper ends of the arms projecting into limiting slots 24 formed in a guide plate 25 supported at its opposite ends on the vertical side brackets 26 secured at their lower ends to the cover plate 22.

Springs 27 yieldingly retain the key levers in, and return them to their normally elevated positions, determined by contact of the upper ends of the key levers with the rear end walls of the limiting slots 24, as shown in Fig. 3.

It is desirable to provide an even key touch wherein each key is depressible by the exertion of the same degree of pressure as every other key, and the difference in lengths of the key levers in the respective banks renders it necessary to provide restoring springs 27 of graduated tensions for the keys of such banks, the weakest set of springs being connected to the key levers 19 of the highest row, whose forward arms are shortest.

Furthermore the evenness of key touch requires that the manually operable keys, irrespective of their lengths, be depressed a like distance, to insure which, the limiting slots 24, through which project the upper arms 19^a of the key levers 19, are graduated in length in accordance with the lengths of the key levers, as shown in Figs. 9 and 10. The upwardly projecting arms of the longest key levers 19 appertinent to the lowest bank of keys enter the shortest limiting slots 24, the upwardly projecting arms of the shortest key levers appropriated to the keys in the highest bank entering the longest slots 24, the slots being arranged in groups, each group comprising a number of slots equal to the number of banks of keys.

The rear ends of the limiting slots 24 lie in alignment, the difference in lengths of the slots being manifest at their forward ends.

The vertical arm of each key lever 19 carries a hooked drag link 28 having a loose connection with the key lever.

In the present instance, such connection is formed by providing the vertical arm of each key lever with a rearwardly projecting fork 29 open at its outer rear end to embrace a stud 30 projecting laterally from the forward end of the drag link. Springs 31 connected at their opposite ends to the respective drag links and to the associated vertical arms of the key levers, yieldingly retain the studs 30 seated in the closed ends of the forks 29.

The drag links extend across the fluted shaft or drive member 130, the free, rearwardly extending noses of the drag links being hooked to normally take over pins 32 projecting laterally from driving thrust links 40, each thrust link constituting a part of the power-actuated linkage for propelling its associated type bar to cause the type to strike the platen 10, the springs 31 urging the drag links into engagement with their pins 32.

The free rear ends of the drag links project through and are retained in guide slots 37 formed in the upper edge of an arresting plate 84 extending between and supported by the opposite side brackets 26 on which the guide plate 25 is mounted. The rear ends of the drag links never wholly disengage their guide slots.

This arresting plate 84 lies at an angle di-

vergent from the drive member 130. The bottom walls of the slots 87 limit the travel of the drag links in clockwise direction, (Fig. 4), under the influence of their springs 31, during the operation of the machine.

The power-operated thrust links 40 in the present illustration of the invention, project upwardly past the opposite side of the rotary drive member 130 from that occupied by the vertical arms 19^a of the manually operated key levers 19, and lie tangentially to the drive member.

Certain of the ascribed objects of the invention are obtained by the particular type of means for transmitting power from the drive member to the intermediate levers 58 and their associated type bars 45.

Thus the arrangement enables the delivery of an impulse to the intermediate lever 58, relieves strain on the less sturdy elements, and effects, in a reliable manner, the automatic disengagement or disconnection of the driven member from the drive member at a predetermined point in a cycle of operations.

To these ends, each thrust link 40 constitutes one member of a toggle mechanism which also includes a radius arm 75 pivoted at 76 on the cover plate 22 of the carriage, to which arm the lower end of the thrust link is pivotally connected at 80, and a connecting or transmitting link 70 pivoted near one end, as at 74, to the radius arm 75 at a point above the pivotal connection 80, the connecting link depending from the radius arm and passing through an opening 73 in the cover plate 22, the lower end of the connecting link being pivotally connected at 71 to 35 the intermediate lever 58 by a stud and spring clip 72 or other convenient fastening.

It will be noted that the pivot 74, connecting the link 70 with the radius arm 75, is located at a distance from the axis of said arm greater than the distance at which the pivot 80, connecting the lower end of the thrust link with the radius arm, is located from the axis of said arm.

The radius arms 75 are journaled on a rod 76 seated in a longitudinally grooved, transversely-slotted bed 77, (see Fig. 13), mounted on the cover plate 22 transversely of the machine.

Screws or other fastening means 78 secure the rod 76 and radius arms against displacement from the bed.

The walls of the respective transverse slots 79 of the bed 77 serve as guides for the several radius arms 75 which rock independently of each other on the fulcrum rod 76.

Each radius arm 75 is conveniently embraced between the adjacent ends of its thrust link 40 and connecting link 70, whereby to promote freedom of action of the parts.

A tensioned spring 85 connected at one end to a toe 86 projecting forwardly from the lower end of the thrust link 40, and at its opposite end to the vertical arm 19^a of the key lever 19 normally holds the toggle mechanism in the flexed position shown in Fig. 3.

A multiple-toothed pawl 81, roughly triangular in shape, is mounted for limited movement on each thrust link 40 above the pivot point 80, and opposite the toothed, rotating drive member 130. In the present embodiment of the invention, the pawl is pivoted by a stud 32 passing into the thrust link through the body-portion of the pawl which lies flat against the side of the thrust link.

The rear edge 83 of the pawl may extend slightly past the rear edge of its associated thrust link when the pawl is in its normal position, to 75

bear against the flat surface of the inclined arresting plate 84, under the influence of the return spring 85, in which position the pawl is out of engagement with the drive member.

5 The forward edges of the pawls 81 facing the drive member 130, each have a lateral lug or offset 88, (Figs. 7, 8 and 11), extending across the front edges of their respective thrust links 40, and two teeth are formed across the combined thicknesses of the lug and the pawl, the outer edge or crest of the upper tooth being somewhat rounded as distinguished from the sharp-edged crest of the lower tooth.

The rear face of the laterally extending lug 88 normally lies in substantial contact with a flat unrecessed portion of the forward edge of its associated thrust link 40, when the mechanism is in its normal or rest position, as shown in Figs. 3, 7 and 11, the lower end of the laterally extending lug 88 overhanging a clearance recess 89 in the front edge of its thrust link, the lower end of which recess forms a shoulder 90 engaged by the lower end of the lateral lug or offset 88 during the operation of the machine, to take the thrust and relieve the pivot pin 82 of strain.

By this arrangement, the trouble caused by breakage of the pawl pivot pins is largely if not wholly avoided.

The free upper or trailing ends of the thrust links 40 travel up and down and rock in guide slots 91 formed in the rear edge of a transverse bar 92 supported at its ends in the opposite side brackets 26.

Operation

With the parts in the normal positions, shown in Fig. 3, it will be seen that manual depression of a key 18, will rock its key lever 19 counterclockwise (in the drawings) on the bearing rod 20, and stress the key return springs 27, the drag link connecting spring 31, and the thrust link return spring 85.

45 The key 18 is arrested at the end of its depression by contact of the upper end of the vertical arm 19^a of the key lever 19 with the forward end of the limiting slot 24, there being sufficient resilience in the key lever to prevent a dead stoppage of the key at the end of the down stroke, and hence the key touch is relieved.

Also, by providing for the arrest of the manually operable keys 18 by contact of the vertical arms of the key levers 19 with the forward ends 55 of the slots 24 upon depression of the keys, the weaker parts, such as the drag link and its connections, are relieved of strain. Jamming of the thrust links between the elements of the interlock (hereinafter explained), when keys are simultaneously depressed is also avoided.

60 Pull on the spring 31 draws the hooked drag link 28 forwardly and with it the corresponding thrust link 50, due to the engagement of the hooked drag link with the pin 32 on the thrust link 40, to straighten the toggle mechanism by moving the thrust link more nearly into alignment with its connecting link 70, and to engage the pawl 81 on the thrust link, with the rotating drive member 130, as illustrated in Fig. 5, 65 wherein the parts are shown in their positions at the instant the pawl is engaged with the drive member.

70 The lower tooth of the pawl first enters the path of a rotating tooth of the drive member, the pawl being so located on the thrust link, by

reason of the incline of the arresting plate 84 with which the rear edge of the pawl normally is aligned, that the lower tooth first moves into engagement with the drive member preferably at a point adjacent a horizontal plane containing the axis of rotation of the drive member.

The flat face of the lower tooth is struck by that tooth of the fluted drive member beneath which the lower tooth lies as it is moved towards the drive member, the tooth of the drive member operating to rock the pawl 81 counterclockwise on its pivot 82 (Fig. 5), until the lower end of the lug or offset 88 of the pawl strikes against the shoulder 90 of the thrust link, the clearance 89 accommodating the rear edge of the lug 88 as the pawl rocks to its effective position.

As the pawl 81 rocks from its normal position, shown in Fig. 7, to its power-transmitting position, shown in Fig. 8, the upper longer tooth of the pawl 81 enters the gullet between the pawl-rocking tooth and the succeeding tooth of the drive member, and the lower sharp-crested tooth disengages from the drive member.

When the lower end of the lug 88 of the pawl seats firmly against the shoulder 90 of the thrust link 40, the drive member 130 operates through the longer upper tooth of the pawl to apply power to the pawl which, in turn, transmits such power through its contact with the shoulder 90, directly to the thrust link 40, and since the thrust link is now nearly aligned with its connecting link 70, the power is transmitted in the form of a sharp impulse to the intermediate lever 58, in a manner closely approximating the manual operation of a key lever, to operate the heretofore-described linkage and rock the type bar 45 to effect an imprint of its type 47.

In delivering the blow of the rotary drive member to the intermediate lever 58, the toggle mechanism travels in a substantially straight line tangential to the rotary drive member, the thrust and connecting links being held substantially in constant relative positions by the radius arm 75 rocking therewith, against the influence of the return spring 85 acting upon the toe 86 of the thrust link, the tension of which spring increases as the toggle mechanism is actuated by the drive member.

Since the pivot 74 is located at a distance from the axis of the arm 75 greater than the distance of the pivot 80 from said axis, the downward movement imparted to the pivot 74 and thereby to the link 70 will be substantially greater than the downward movement imparted to the thrust link 40 and to the pivot 80. It will be noted by reference to Figures 3 and 5, that, when the thrust link 40 and connecting link 70 are in their uppermost positions ready to start a downward stroke, the radius arm 75 is in a position such that the pivot 74 is adjacent the top of the arc described thereby during the downward stroke of said links. This results in imparting an accelerated movement in a downward direction to the pivot 74 and to the link 70 and a corresponding accelerated stroke to the lever 58 and to the type bar actuating mechanism connected therewith. The parts are preferably so arranged that, as the links 40 and 70 approach the end of their downward movement, as shown in Figure 4, the point of contact of the tooth on the rotating drive member with the upper tooth on the pawl, is brought into a position relatively close to the line connecting the axis 75

of said drive member with the center of the pivot 80.

The engagement of the longer upper tooth of the pawl 81 with the rotating drive member, 5 and the actuation of the pawl and thrust link by the drive member overcomes the tendency of the return spring 85 to disengage the thrust link and pawl from the drive member.

And to guide the thrust link 40 during the 10 final driving travel thereof, and hold the same against the lateral pull of the drive member on the pawl, the upper free or trailing end of the thrust link is faced on its forward edge, as at 93, to ride along its particular finger 94 (Figs. 15 9 and 10) of a series of fingers formed on the rear edge of the guide plate 25 by slitting the guide plate at points in line with the intervals between the thrust links.

The faced portion 93 on the trailing end of the thrust link 40 lies apart from its guide finger 94 throughout the greater part of the effective stroke of the type action, and does not contact its finger until near the end of the effective stroke when the radius arm 75 and its pivotal connection 80 have been rocked nearly to the lowest point, whereupon, as a result of the continued clutching action between the pawl and the drive member as the pawl rides down under the drive member, and also because of the shift 25 30 35 towards the drive member imparted to the lower end of the thrust link by its radius arm, as the latter approaches its horizontal position, the faced edge 93 contacts its guide finger to guide the thrust link in its further longitudinal movement, and preserve the tangential relation of the links 40 and 70 relatively to the drive member 130.

As a result, the thrust link is moved longitudinally in a line tangent to the rotating drive 40 member under the guidance of the radius arm 75 and of the guide finger 94 during the latter part of its movement. The drive member, therefore, operates, when the point of engagement of the drive member with the pawl approaches 45 relatively closely to the line connecting the axis of the drive member with the center of the pivot 80, to cast off the pawl, the thrust and connecting links continuing to move in the same direction under the impetus imparted thereto by the drive member, until arrested, as by contact of the type 47 with the platen 10 or the work thereon.

At the completion of the disengagement of the pawl 81 from the drive member 130, the tensioned 55 return spring 85 connected to the toe 86 of the thrust link 40, rocks the thrust link and pawl away from the drive member and holds them in such disengaged relation, as the spring 48 assisted by the spring 85, restores the parts to their 60 normal positions of rest.

The pawl 81, after having been rocked by its engagement with the drive member 130 to contact its lower end with the shoulder 90 of the thrust link, remains in such rocked position during 65 the remainder of the effective stroke, the pawl traveling downwardly and forwardly with the link under the dual influences of the clutching action between the pawl and drive member, and of the radius arm 75 as it shifts towards 70 its horizontal position, until near the end of such effective stroke, the rear edge of the pawl being spaced apart from the inclined arresting plate 84, and lying at an angle thereto, as shown in Fig. 4.

As the return spring 85 rocks the thrust link

backwardly away from the drive member after the tangential disengagement of the pawl from the drive member, the rear edge of the pawl strikes the inclined face of the arresting plate 84 and is cammed thereby to rock in clockwise direction back to its normal position relatively to its thrust link (Fig. 7), the pawl thereafter sliding up the inclined face of the arresting plate as the springs 48 and 85 complete the restoration of the parts to normal position.

The faced free end of the intermediate lever 58, by its contact with the cushioning stop 64, arrests the parts upon their return to normal positions.

It will be particularly noted that the foregoing mechanism differentiates from the patents to Schlüns and to Schulze heretofore referred to, in that in the patented structure, the fluted, rotary drive member exercises a pulling action on the type bar linkage, whereas the present arrangement exerts a driving or pushing force.

In the construction illustrated and described in this application, the pawl is arranged to be automatically thrown or cast out of engagement with the drive member at a time when the pawl is nearly at the bottom of the rotation of the drive member. The parts are preferably arranged so that the pawl is cast off from the drive member when the point of contact of the drive member with the upper tooth of the pawl is adjacent the line connecting the center of the pivot 80 with the axis of the drive member, as stated above, and a little more or little less travel of the pawl with the drive member will have no material effect, thus avoiding the necessity for the exact and careful adjustment required when the type action is pulled on its effective stroke. Also the most desirable point at which the cast off or disengagement of the pawl and drive member should be effected, can be readily secured by adjustment of the corresponding guide finger 94.

Key interlock

A channel or groove 95 formed longitudinally of the guide bar 92 intersects the several guide slots 91 for the thrust links, a series of interlocking elements, as balls 96, being confined in the longitudinal groove, between adjusting members, as studs 97 (Figs. 9 and 10), projecting into the opposite ends of the groove and acting as pilots for springs 98 pressing against the balls at the respective opposite ends of the series, to center the series in the groove.

As is usual in this type of interlock, the combined space between the end balls of the series and the ends of the studs 97, is just equal to the width or thickness of a single thrust link 40, whereby to enable the interposition of a single thrust link between the balls, which will be separated thereby into two series, each of which will be crowded towards its respective end of the groove until arrested by contact of the end ball in each series with the appropriate stud 97, whereupon the separated series of balls will present an unyielding wall against the entry of a second thrust link therebetween so long as the first-named thrust-link remains in its interposed position.

The above-described interlock is so arranged relatively to the "throw" of the thrust links 40, as to arrest the thrust links before the pawls 81 can engage the drive member 130.

By associating this interlock with the power-driven section of the key action rather than with the manually operable section thereof, the ma-

chine is capable of a far greater speed of operation, without any danger of piling up the type bars.

Also the operation of the machine is less fatiguing as the operator may, in effect, rest his hands on the keyboard as he operates the successive keys.

Indeed, with the interlock effective upon the power driven section of the key action, it is possible to retain one or more manually operable key levers depressed, while operating the remaining keys, the continued depression of such manually operable key levers interfering in no manner with the operation of the other key actions, because the manually operable levers are not controlled by the interlock.

Simultaneous depression of two or more keys 18 will tension the springs 31 to advance their respective drag links 28 and rock the corresponding thrust links 40 until their forward edges contact the interlocking elements 96, whereupon the thrust links and their drag links 28 are arrested, but the connecting springs 31 permit the keys 18 to complete their full depressions, to preserve the "touch," and prevent jamming the thrust links and the key interlock.

If, upon depression of a key 18, the flattened flank of the lower tooth of the pawl strikes the crest of one of the teeth of the rotary drive member 130, the spring 31 will yield to prevent the imposition of strain on the parts, and will snap the pawl into mesh with the drive member as soon as the obstructing tooth of the latter escapes the lower tooth of the pawl.

Should the operator, intentionally or otherwise, maintain the key depressed throughout the power driven operation of the type action, no harm will result.

The drive member 130 will, of course, propel the thrust link and its pin 32 downwardly away from the advanced drag link 28 to terminate the manual control of the thrust link, and the drag link will follow, due to the action of the spring 31, until its rear end rests on the bottom of the slot 87 of the inclined arresting plate 84, in which position it will remain until the pin 32, on its return to normal with its thrust link 40, strikes the dwell 99 formed on the bill of the hooked drag link and swings the drag link upwardly about the pivot stud 30.

No repeat operation of this type action can occur until the operator releases the key to the action of its spring 27, which thereupon rocks the key lever 19 clockwise, and shifts the drag link rearwardly, the dwell 99 riding on the pin 32 until the hooked portion drops over the pin to again enable the key to control its thrust link.

This play of the pawl up and down and back and forth has no effect on the operation of the type action and precision workmanship on the pawl is unnecessary.

Escapement control

The intermediate lever 58, when rocked by the thrust imparted thereto by the toggle mechanism, operates to trip the escapement 33, as shown in Patent 1,203,519.

The adjustable screw 141, (Fig. 3), carried by each of the intermediate levers 58 strikes a horizontal universal bail 142 extending transversely of the key carriage just beneath the series of intermediate levers 58, and suspended from a pair of forwardly extending arms 143 fast on a trans-

versely extending shaft 144 suitably supported at its ends for rocking movement.

Depression of the universal bail against the tension of its return spring 140 by any of the intermediate levers will rock the shaft 144 counter-clockwise, and with it a rearwardly extending arm 145 connected by a turn-buckle link 146 to the spacing pawl 147 of the escapement mechanism 33 to trip the latter, all as more fully disclosed in Patent 1,203,519. The carriage feed pinion 148 and carriage feed rack 149 are shown in Fig. 11, the rack being fast to the rear rail 14 of the line space frame 13.

The usual space bar 150, (Fig. 11), instead of directly tripping the escapement, as heretofore, is also arranged to control the escapement through the power drive mechanism of this invention.

To this end, the space bar is supported at the outer ends of a pair of arms 151 projecting forwardly from a shaft 152 extending horizontally between, and suitably journaled at its ends in the side frames 60 of the key carriage.

A spring 153 connected to a rearwardly projecting arm 154 on the space bar shaft 152 normally retains the space bar in elevated position, the arm 154 being recessed, as at 155, to accommodate and guide the universal bail 142 when depressed by the intermediate levers 58.

A link 156 pivotally connects one of the forwardly projecting arms 151 with the forward arm 157 of an angle lever journaled on the same fulcrum rod 20 with the key levers 19, 19a.

The upwardly projecting arm 158 of the angle lever projects through a slot 23 in the cover plate 22, and the free end of the arm 158 is confined in a slot 24a in the cover plate 25, a spring 27a operating in conjunction with the spring 153, to hold the vertical arm 158 at the rear end of the slot.

A stud 30 on the forward end of a drag link 28 loosely seats in a fork 29 formed on the vertical arm 158, a spring 31 retaining the stud yieldingly at the closed end of the fork, and also fitting the rear hooked end of the drag link over a pin 32 projecting laterally from a thrust link 40, the lower end of which link is pivoted, as at 30, to the free end of a radius arm 75 journaled on the fulcrum bar 76.

A spring 85 connected to the projecting toe 86 of the thrust link 40 and to the vertical arm 158, normally holds the thrust link withdrawn from the continuously rotating drive member 90. A toothed pawl 81, in all respects like the pawls on the thrust links corresponding with the keys 18, is pivoted at 82 to the space bar thrust link, which link co-acts with the key interlocking balls 96, and is supported and alined by the arresting plate 84 which limits rearward travel of all the thrust links 40.

A connecting link 159 pivoted at 74 to the radius arm 75, depends through an opening 73 in the cover plate 22 and is bifurcated at its lower end, as at 160, to embrace a headed stud 161 projecting laterally from one of the arms 143 supporting the universal bail 142.

The bifurcation is of sufficient length to enable the connecting link 159 to retain its engagement with the stud, when the universal bail supporting arm 143 is rocked by operation of one of the intermediate levers 58, and a shoulder 162 on the connecting link 159 is arranged to collide with the under face of the cover plate 22 adjacent the opening 73 to arrest the thrust link 40 against excess upward travel under the in-

fluence of the universal bar restoring spring 140.

Cushioning means 163 on the space bar or key 150 contacts the upper edge of the front bar of key carriage frame 60 when the key 150 is depressed against the tension of its return spring 153.

The space bar or key when so depressed, pulls the link 156 downwardly to rock the angle lever 157, 158 forwardly, which in turn, draws the drag link 28 forwardly, and tensions the spring link 31.

The spring link rocks the thrust link 40 forwardly to bring it more nearly into alignment with its co-acting connecting link 159, and to engage the pawl 81 with the drive member 90, whereupon the pawl is rocked to seat its lug against the shoulder 90 on the thrust link, after which the drive member impels the thrust and connecting links downwardly to rock the arm 143, shaft 144, and arm 145 clockwise (Fig. 11), thus raising the turn buckle link 146 to operate the spacing dog 147, just as when a key 18 is depressed.

The pawl 81 and thrust link 40 are automatically cast off from the drive member, as heretofore explained in connection with the description of the operation of a key 18, whereupon the spring 85 rocks the thrust link away from the drive member, and with the assistance of the return spring 140, restores the power-driven parts to their normal positions.

Continued depression of the space key or bar 150 merely prevents the effective connection of the drag link 28 with the restored thrust link 40, the same conditions and advantages prevailing as heretofore explained.

Changes may be made in the form and arrangement of the several novel features heretofore set forth, without departing from the spirit and scope of this invention.

What is claimed as new is:

1. In a writing machine, the combination with a power-actuated drive member; and a driven member; of a link adapted to thrust against the driven member; a pawl pivotally mounted on the thrust link; a key lever; means to releasably connect the key lever and the thrust link, to effect engagement of the pawl with the drive member; and means on the thrust link, engaged by the pawl as a result of its rotation relatively to the thrust link upon the engagement of the pawl with the drive member, to transmit the direct thrust of the drive member to the thrust link, and relieve the pawl pivot of strain.

2. In a writing machine, the combination with a power-actuated drive member; of a type bar train, including a thrust link and a type bar; a pawl pivotally mounted on the thrust link, and having an offset; a shoulder on the thrust link with which the offset coacts; a key lever; and means to releasably connect the key lever and the thrust link, to effect engagement of the pawl with the drive member, whereby, on such initial engagement, the drive member rotates the pawl to contact its offset with the shoulder on the thrust link to transmit the power directly from the drive member to the thrust link, and relieve the pawl pivot of strain.

3. In a writing machine, the combination with a power-actuated drive member; of a type bar train, including a thrust link, and a type bar; a pawl pivotally mounted on one side of the thrust link, and having a lateral extension projecting into the path of the thrust link; the rear face of the lateral extension opposing the front edge of

the thrust link; a shoulder on the thrust link, normally located apart from the lower end of the lateral extension; and a key lever to effect engagement of the pawl with the drive member, whereby initial rotation of the pawl relatively to the thrust link is arrested by contact of the lower end of the lateral extension with the shoulder on the thrust link, to transmit the thrust of the drive member to the type bar train, and relieve the pawl pivot of strain.

4. In a writing machine, the combination with a power-actuated drive member; of a type bar train, including a driving thrust link; a pawl mounted thereon; a rocking radius arm to which one end of the thrust link is pivoted; a type bar; a lever with connections to the type bar, and a connecting thrust link pivoted to the radius arm and the lever; means to rock the driving link about its pivot to effect engagement of the pawl with the drive member, whereby the driving link is brought into position to enable the drive member to deliver a direct thrust to the driving link to produce a thrust movement of the connecting link and thereby to actuate the lever to simulate a manual operation of the lever; and means for engaging the driving link to cause the disengagement of the pawl from the drive member.

5. In a writing machine, the combination with a power-actuated drive member; of a rocking radius arm located on one side of the drive member; a thrust link and a connecting link, the adjacent ends of which are pivotally connected to the radius arm, the thrust link extending tangentially past the drive member, and carrying a pawl; a lever to which the opposite end of the connecting link is pivoted; a type bar; a linkage connecting the lever and type bar; a guide for the trailing end of the thrust link, and located on the opposite side of the drive member from the radius arm; a key lever; and means releasably connecting the key lever and thrust link to rock the latter towards the drive member, to engage the pawl with the drive member, at a point to one side of a vertical line through the center of the drive member, to enable the drive member to impart motion to the thrust and connecting links in the direction of their lengths, the pawl following downwardly around the drive member under control of the trailing end of the thrust link, and the guide, to a point near the vertical center line of the drive member, from which it is automatically cast off by the drive member by the movement imparted to the thrust link.

6. The adaptation of a power-drive to a key-operated type bar action, including a power-actuated drive member; a rocking radius arm located between the type bar action and the drive member; links arranged in tandem and respectively pivoted to the radius arm, one of the tandem links arranged tangentially of the drive member, and carrying a pawl, the remaining tandem link pivotally connected to the type bar action; and means to move one of the tandem links transversely of its length, to engage the pawl with the drive member, and to enable the drive member to deliver a longitudinal thrust along the tandem links, and thereby operate the type action, to simulate a manual operation.

7. In a writing machine, the combination with a power-actuated drive member; of a type bar linkage, including a type bar, a bell crank, a reversing lever, an intermediate lever and their connecting rods, a radius arm; a connecting link pivoted to the radius arm and to the intermediate lever, respectively; and a thrust link pivotally

supported at one end on the radius arm and extending tangentially past the drive member; a pawl on the thrust link; a key lever to rock the thrust link and engage the pawl with the drive member; and a guide for the trailing end of the thrust link, which coacts with the radius arm in guiding the thrust and connecting links during the engagement of the pawl with the drive member, to enable the drive member to automatically cast off the pawl as the point of engagement of the drive member with the pawl approaches a vertical plane containing the axis of the drive member.

8. In a writing machine, the combination with a power-actuated drive member; and a plurality of type bar linkages, each including a thrust link and pawl driven by the drive member; of a guide comb for the thrust links, the fingers of which comb may be variously positioned to enable an adjustment of the points of disengagement of the pawls and the drive member under the impetus imparted to the thrust links by the drive member.

9. In a writing machine, the combination with a power-actuated drive member; and a plurality of type bar linkages, each including a pivotally supported thrust link, and a pawl mounted on the thrust link; of key levers individual to the respective thrust links, and arranged in banks, the key levers of one bank differing in length from the key levers of another bank; means to releasably connect the key levers and their thrust links; projecting arms on the key levers; and a plate having slots of varying lengths entered by the projecting arms of the key levers of varying lengths to afford like extents of depression to the several key levers irrespective of their lengths.

10. In a writing machine, the combination with a power-actuated drive member; and a type bar linkage, including a thrust link, and a pawl mounted on the thrust link; of a manipulative member; a hooked drag link carried thereby; a projection on the thrust link normally engaged by the hook of the drag link, to enable the manipulative member to rock the thrust link and engage the pawl with the drive member, the drive member adapted to impel the thrust link in the direction of its major axis away from the drag link; and means to rock the thrust link and its pawl away from the drive member, and to return the thrust link to its normal position, the nose of the drag link being of sufficient length to lie in the path of, and be contacted by the projection on the thrust link on the return of the latter, while the manipulative device remains depressed.

11. In a writing machine, the combination with a rotatable, power-actuated, toothed drive member; and a type bar linkage, including a type bar; of means to transmit power from the drive member to the type bar linkage, including a thrust member connected with the type bar linkage, and having a thrust-sustaining bearing; a pawl shiftably mounted on the thrust member, and normally spaced apart from the thrust-sustaining bearing; and means to engage the pawl with the drive member, whereby the latter initially shifts the pawl to contact the thrust-sustaining bearing, to enable the pawl to transmit power to the thrust member through the bearing.

12. In a writing machine, the combination with a drive member; and a driven member; of means to transmit power from the drive member to the driven member, including a

thrust member to actuate the driven member; a pawl pivoted on the thrust member, and normally out of engagement with the driven member; an abutment on the thrust member to limit travel in one direction of the pawl relatively to the thrust member; the pawl normally lying apart from the abutment; and means to engage the pawl with the drive member, whereby the latter initially shifts the pawl into contact with the abutment, to transmit motion to the thrust member through contact of the pawl and abutment, and thereby receive the pawl pivot of strain.

13. In a writing machine, the combination with a driven member; and a rotatable drive member; of means to transmit movement to the driven member from the drive member, including a toggle mechanism comprising a thrust link, a connecting link, and a rocking radius arm, the adjacent ends of the links being separately pivoted to the radius arm at respectively different distances from its axis of rotation; the pivot points of the links normally lying to one side of the vertical plane of the longitudinal axis of the drive member; the opposite end of the connecting link being arranged to deliver an impulse to the driven member; a pawl on the thrust link; a guide for the thrust link; and means to engage the pawl with the drive member, whereby the latter, in its rotation, imparts endwise movement to the links and rocks the radius arm until the point of engagement of the pawl with the drive member lies adjacent the line connecting the center of the pivotal connection between the thrust link and the radius arm with the axis of rotation of the drive member, so that continued movement of the drive member will cast off the pawl therefrom.

14. In a writing machine, the combination with a driven member; and a rotatable drive member; of means to transmit movement from the drive to the driven member, including a thrust link, a rocking radius arm to which the thrust link is pivoted, and means to connect the radius arm and the driven member; a pawl on the thrust link; a guide for the trailing end of the thrust link; and means to engage the pawl with the drive member, whereby the latter, in its rotation, imparts endwise movement to the link and rocks the radius arm until the point of engagement of the pawl with the drive member lies adjacent the line connecting the center of the pivotal connection between the thrust link and radius arm with the axis of the drive member, to enable the drive member to cast off the pawl.

15. In a writing machine, the combination with drive and driven members; of mechanism to impart motion from the drive to the driven member, including a toggle lever, and a radius arm; one link of the toggle lever being connected with the driven member and to the radius arm, respectively; the remaining link of the toggle lever being also connected near one end to the radius arm; a pawl on said remaining link of the toggle lever; a manually operable lever; and means controlled by the manually operable lever and releasably connected to the toggle lever to actuate the latter to engage the pawl with the drive member.

16. In a writing machine, the combination with a type action; of power means to actuate the type action, including a constantly rotating, toothed drive member; a toggle mechanism adapted to transmit power from the power means

to the type action, the toggle mechanism including toggle links, and a stationarily pivoted radius arm, to which the adjacent ends of the toggle links are individually pivoted; a pawl on one of the toggle links; manually operable means to rock the pawl-carrying toggle link to engage the pawl with the drive member; and a guide means for the trailing end of the pawl-carrying toggle link.

17. In a writing machine, the combination with a type action; and a rotary, toothed drive member therefor; of a toggle mechanism arranged tangentially of the rotary drive member, and including a pair of toggle links, and a stationarily fulcrumed radius arm interposed between the adjacent ends of the toggle links; the adjacent ends of the toggle links being individually pivoted to the radius arm at relatively eccentric points; a pawl carried by one of the toggle links; means to rock the pawl-carrying toggle link in one direction with relation to its complementary toggle link, to engage the pawl and drive member; a guide for the trailing end of the pawl-carrying toggle link, cooperating with the radius arm to guide said link prior to the disengagement of the pawl and drive member; and means to rock the pawl-carrying link in the opposite direction, away from the drive member, subsequently to the disengagement of the pawl from the drive member.

18. In a power-driven writing machine, the combination with a type bar; and a drive member therefor; of power-transmitting means interposed between the type bar and the drive member, and normally disconnected from the drive member, including a toggle mechanism arranged tangentially alongside the drive member, the toggle mechanism comprising a pair of links; a stationarily pivoted radius arm to which one end of each of the links is individually pivoted; a pawl located on one of the links opposite the drive member; and means to rock the pawl-carrying link with relation to its co-acting link to engage the pawl with the drive member at a point adjacent a horizontal plane through the center of the drive member on its driving side to enable the drive member to impart an impelling force to the toggle mechanism in a direction tangential to the direction of travel of the drive member, whereby to automatically cast off the pawl as the latter, in its travel with the drive member, reaches a point under the drive member wherein the point of engagement of the pawl with the drive member lies adjacent a line connecting the center of the pivotal connection between the pawl carrying link and the radius arm with the axis of rotation of the drive member.

19. In a power-driven writing machine, the combination with a traveling carriage; a relatively stationary support for the carriage; and an escapement to effect a step-by-step feed of the carriage relatively to its support; of a drive member mounted to rotate in the carriage and to travel therewith; sectional key actions mounted in the carriage to travel therewith, each key action including a manually operable section, and a mechanically driven section, respectively, the mechanically driven sections each including a type bar; means on each mechanically driven section for releasably engaging the drive member, under control of its co-related manually operable section, to enable the drive member to actuate the type bar; means to return the mechanically driven section to normal position; a motor on the relatively stationary support; a

jack shaft driven from the motor; a power-transmitting element mounted to travel along the jack shaft; and connections between the power transmitting element and the drive member, the connections and power-transmitting element shifting with the traveling carriage.

20. In a power-driven writing machine, the combination with a traveling carriage; a relatively stationary support for the carriage; and an escapement to effect a step-by-step feed of the carriage relatively to its support; of a drive member mounted to rotate in the carriage and to travel therewith; sectional key actions mounted in the carriage to travel therewith, each key action including a manually operable section, and a mechanically driven section, respectively, the mechanically driven sections each including a type bar; means on each mechanically driven section for releasably engaging the drive member, under control of its co-related manually operable section, to enable the drive member to actuate the type bar; means to return the mechanically driven section to normal position; a source of power on the relatively stationary support; and connections between the drive member and the source of power, and traveling with the carriage.

21. In a power-driven writing machine, the combination with a traveling carriage; a relatively stationary support for the carriage; and an escapement to effect a step-by-step feed of the carriage relatively to its support; of a drive member mounted to rotate in the carriage and to travel therewith; sectional key actions mounted in the carriage to travel therewith, each key action including a manually operable section, and a mechanically driven section, respectively, the mechanically driven sections each including a type bar; means on each mechanically driven section to releasably engage the drive member under control of its co-related manually operable section, to enable the drive member to actuate the type bar; and means to return the mechanically driven section to normal position upon its release from the drive member; a motor on the relatively stationary support; a jack shaft driven from the motor; a power-transmitting element mounted to travel along the jack shaft; and connections between the power-transmitting element and the drive member, and shifting with the traveling carriage.

22. In a power-driven writing machine, the combination with a plurality of banks of manually operable keys arranged in different horizontal planes; key levers for the respective keys of each bank; a common fulcrum for the key levers, the key levers of successive banks from highest to lowest being respectively longer than the key levers of the preceding bank; a drive member; type bar actions appropriate to the respective keys; and means actuated by the respective manually operable key levers to positively engage the corresponding type bar actions with the drive member; of means to insure uniform depression of the keys of all banks to like extents irrespective of the different lengths of key levers, for the purpose of preserving the key touch, including arms of uniform length projecting from the respective key levers; and a motion-limiting plate having slots of different lengths to accommodate the projecting arms.

23. In a power-driven writing machine, the combination with a drive member; of a plurality of banks of key actions, each key action including a manually operable key lever, and a mechanical-

ly operated type bar action, the key levers of any bank differing in lengths from the key levers of any other bank; a common fulcrum for all keys; and means whereby, upon depression of the manually operable key levers, motion is transmitted to the corresponding key actions to engage the latter with the drive member; of means to maintain uniform the extent of depression of the keys of all banks notwithstanding differences in the lengths of the key levers, including arms projecting from the key levers; and stops graduated in correspondence with the lengths of the associated key levers, to limit the depressive movement of such levers.

15 24. In a writing machine, the combination with a power-actuated drive member; and a driven member; of a normally idle thrust link to impart motion to the driven member; a pawl pivotally mounted on the thrust link; a key lever; means operable by the key lever to shift the thrust link to engage the pawl with the drive member; and means on the thrust link and contacted by the pawl when rotated on its pivot by the drive member as a result of its engagement therewith, to transmit the direct thrust of the drive member to the thrust link, and thereby relieve the pawl pivot of strain.

20 25. In a writing machine, the combination with a power-actuated drive member; and a driven member; of a normally idle thrust link to impart motion to the driven member; a pawl loosely connected to the thrust link; a key lever; means operable by the key lever to shift the thrust link to engage the pawl with the drive member; and thrust-sustaining means on the thrust link against which the pawl is pressed incident to its engagement with the drive member, to transmit the direct thrust of the drive member to the thrust link, to relieve the pawl connection of strain.

30 26. In a writing machine, the combination with a type action; and a rotary, toothed drive member therefor; of a toggle mechanism arranged tangentially of the rotary drive member, and including a pair of toggle links, and a stationarily fulcrumed radius arm interposed between the adjacent ends of the toggle links; the adjacent ends of the toggle links being individually pivoted to the radius arm at different distances from its axis of rotation; a pawl carried by one of the toggle links; means to rock the pawl-carrying toggle link in one direction with relation to its complementary toggle link to engage the pawl and drive member; and means to rock the pawl-carrying link in the opposite direction with relation to the remaining toggle link, away from the drive member, subsequently to the disengagement of the pawl from the drive member.

35 27. In a power-driven writing machine, the combination with a traveling carriage; a relatively stationary support for the carriage; and an escapement to effect a step-by-step feed of the carriage relatively to its support; of a drive member mounted to rotate in the carriage and to travel therewith; sectional key actions mounted in the carriage to travel therewith, each key action including a manually operable section, and a mechanically driven section, respectively, the mechanically driven sections each including a type bar; means on each mechanically driven section to releasably engage the drive member under control of its co-related manually operable section, to enable the drive member to actuate the type bar; a motor on the relatively stationary support; a jack shaft driven from the motor; a

power-transmitting element mounted to travel along the jack shaft; and connections between the power-transmitting element and the drive member, and shifting with the traveling carriage.

28. In a power-driven writing machine, the combination with a traveling carriage; a relatively stationary support for the carriage; and an escapement to effect a step-by-step feed of the carriage relatively to its support; of a drive member mounted to rotate in the carriage and to travel therewith; sectional key actions mounted in the carriage to travel therewith, each key action including a manually operable section, and a mechanically driven section, respectively, the mechanically driven sections each including a type bar; means on each mechanically driven section to releasably engage the drive member under control of its co-related manually operable section, to enable the drive member to actuate the type bar; and means to return the mechanically driven section to normal position upon its release from the drive member; a motor stationary in the direction of movement of the carriage to actuate the drive member and driving connections between said motor and the drive member, having means to accommodate the movement of the drive member with the carriage.

29. In a power-driven writing machine, the combination with drive and driven members; of a toggle lever to transmit motion from the drive to the driven member, a pawl mounted on the toggle lever, and normally disconnected from the drive member, manually controlled means to actuate the toggle lever to engage the pawl with the drive member; and means operable upon the toggle lever to limit the duration of engagement of the pawl and drive member, and effect disengagement thereof at a predetermined point in the rotation of the drive member.

30. A writing machine having, in combination, a power actuated drive member, a plurality of type bars, connections respectively for actuating the type bars from the drive member each including a longitudinally movable link and a pawl engageable with the drive member and a guide comb for said links having fingers for engaging the links adjustable in different positions to adjust the points of disengagement of the pawls from the drive member.

31. A writing machine having, in combination, a power actuated drive member, a plurality of type bars, mechanisms respectively for actuating the type bars from said drive member each including a longitudinally movable link, a pawl loosely mounted on said link and arranged to engage the drive member and an abutment on said link arranged to engage the pawl in the line of thrust of said drive member on the pawl to limit the free movement of the pawl when engaged with said drive member.

32. A writing machine, having, in combination, a rotatable power actuated toothed drive member, a series of type bars, connections respectively for actuating the type bars from said toothed drive member each comprising a pawl carrying bar, a pawl loosely mounted on said bar for pivotal movement between certain limits, a thrust sustaining bearing on said bar for engaging the pawl in substantially the line of thrust of said rotatable member on the pawl and means for shifting the bar to engage the pawl with the drive member.

33. A writing machine having, in combination, a power actuated drive member, a plurality of type bar linkages each including a pawl carrying link

and a pawl carried by said link for engaging the drive member and individually adjustable means for engaging respectively the trailing ends of the pawl carrying links to enable an adjustment of the points of disengagement of the pawls and drive member to be effected.

34. A writing machine having, in combination, a rotatable power actuated toothed drive member, a series of type bars, mechanisms respectively for actuating the type bars from said toothed drive member each comprising a driving thrust link moved longitudinally from the drive member, a connecting thrust link moved longitudinally from the driving link, means for connecting and guiding the adjacent ends of said links, a pawl carried by the driving link for engaging the drive member to cause the drive member to deliver a thrust to the driving and connecting links to actuate the corresponding type bar to engage the type with the work and a device for engaging the driving link to cause the disengagement of the pawl from the drive member.

35. A writing machine having, in combination, a rotatable power actuated toothed drive member, a series of type bars, connections respectively for actuating the type bars from said toothed drive member each comprising a driving thrust bar moved longitudinally by the drive member, a connecting thrust link moved longitudinally by the thrust bar, a pivoted member for connecting the adjacent ends of said link and said bar, a pawl carried by said thrust bar for engaging the drive member to cause the drive member to deliver a thrust to the driving bar and the connecting link to actuate the corresponding type bar to engage the type with the work and a device for engaging the driving bar to disengage the pawl from the drive member.

36. A writing machine having, in combination, a rotatable power actuated drive member, a series of type bars, means for actuating a type bar from the drive member comprising a longitudinally movable driving link, a device carried by said link for engaging the rotatable drive member, a longitudinally movable transmitting link connected with the first link and with a type bar and substantially aligned with said driving link when in operation and connecting devices between said links arranged to control the transmitting link to cause a relatively slow starting movement and a gradually accelerated movement to be imparted thereto from the first link to drive the transmitting link from the driving link at substantially its maximum speed adjacent the end of its type bar actuating movement.

37. A writing machine having, in combination, a drive member continuously rotated by power, a plurality of type bars, means for actuating the type bars from the drive member, each comprising a longitudinally movable actuator thrust link, a device connected with said link for engaging the rotatable drive member, a longitudinally movable transmitting thrust link connected with said first link, a connection between the latter link and a type bar and connecting means between said links arranged to actuate the transmitting link from the first link and to cause greater movement to be imparted to the transmitting link than the movement of the first link.

38. A writing machine having, in combination, a continuously rotating power drive member, a series of type bars, means for actuating a type bar from the drive member comprising a longitudinally movable thrust actuator arranged to be driven from said drive member, a radius arm

pivoted to swing in the general direction of movement of the actuator, a pivotal connection between the actuator and the radius arm for swinging the arm, a transmitting thrust link, a pivotal connection between the arm and the transmitting link located at a greater distance from the axis of the arm than said first pivotal connection and arranged to impart a relatively slow starting movement and a gradually accelerated movement to the transmitting link from the actuator and a connection between the transmitting link and the type bar for actuating the type bar.

39. A writing machine having, in combination, a rotatable power actuated drive member, a plurality of type bars, means for actuating the type bars from the drive member, each comprising an actuator bar arranged to be driven longitudinally by said drive member, an arm pivoted to swing in the general direction of movement of said actuator bar, a pivotal connection between said actuator bar and the arm for swinging said arm, a longitudinally movable transmitting link connected with a type bar and substantially aligned with the actuator bar in operation and a pivotal connection between the transmitting link and said arm arranged to impart a relatively slow starting movement and a gradually accelerated movement to the transmitting link from the movement of the actuator bar and to drive the transmitting link at substantially its maximum speed adjacent the ends of its type bar actuating movement.

40. A writing machine having, in combination, a continuously rotated power drive member, a series of type bars, means for actuating a type bar from the drive member, comprising a longitudinally movable actuator bar, a device connected with said actuator bar for engaging the rotatable drive member to impart longitudinal movements to said bar, an arm pivoted to swing in the general direction of movement of said actuator bar, a pivotal connection between the actuator bar and the arm for swinging said arm, a transmitting link connected with a type bar, arranged for longitudinal movement to actuate the type bar and substantially aligned with the actuator bar in operation and a pivotal connection between the transmitting link and the arm arranged to impart a relatively slow starting movement and a gradually accelerated movement to the transmitting link in a type bar actuating direction and of greater magnitude than the movement of the actuator bar and to drive the transmitting link at substantially its maximum speed adjacent the end of its type bar actuating movement.

41. A writing machine having, in combination, a drive member continuously rotated by power, a plurality of type bars, means for actuating the type bars from the drive member, each comprising a longitudinally movable driving thrust link, means carried by said link for engaging the drive member to cause a thrust movement to be imparted to the driving link, a longitudinally movable transmitting thrust link connected with the driving link and with a type bar and devices connecting the driving link and the transmitting link for actuating the transmitting link from the driving link and controlling the transmitting link to cause a relatively slow starting movement and a gradually accelerated movement to be imparted thereto from the driving link.

42. A writing machine having, in combination,

5 a rotatable power actuated drive member, a series of type bars, means for actuating the type bars from the drive member, each comprising a thrust actuator to which thrust movements are imparted by said drive member to actuate a type bar, a control arm pivoted to swing upon a fixed axis, a pivotal connection between said actuator and the arm for swinging said arm, a longitudinally movable transmitting thrust link connected with the type bar and a pivotal connection between the transmitting link and said arm arranged to impart a relatively slow starting movement and a gradually accelerated movement to the transmitting link from the movement of the actuator. 10 43. A writing machine having, in combination, a rotatable power actuated drive member, a plurality of type bars, means for actuating the type bars from the drive member, each comprising a thrust actuator, a device connected with said actuator for engaging the drive member to cause thrust movements to be imparted to the actuator, a control arm pivoted to swing upon a fixed axis, a pivotal connection between the actuator and said arm for swinging the arm, a transmitting thrust link connected with a type bar and a pivotal connection between the transmitting link and the arm arranged to impart a relatively slow starting movement and a gradually accelerated movement of greater magnitude than the movement of the actuator to the transmitting link to actuate the type bar.

44. A writing machine having, in combination, a rotary toothed power driven driver, a plurality of type bars, means for actuating the type bars from said driver, each comprising a thrust link, a tooth carried by the thrust link for engaging said driver, means for moving the thrust link transversely of its length to engage the tooth with the driver and a device for engaging the trailing end of said link to cause the disengagement of the tooth from the driver.

45. A writing machine having, in combination, a continuously rotated toothed power drive member, a series of type bars, means for actuating the type bars from the drive member, each comprising a longitudinally movable thrust link, a projection carried by said link for engaging the drive member, means for pivotally supporting the link at its forward end to enable the same to swing toward and from the drive member, mechanism for swinging the link about the pivot at its forward end to engage the projection carried thereby with the drive member and a device for engaging the trailing end of the link to cause the disengagement of the projection from the drive member.

46. A writing machine having, in combination, a rotary toothed power driver, a plurality of type bars, means for actuating each of the type bars from the driver comprising a driving thrust link, toothed means carried by said link for engaging the driver to cause thrust movements to be imparted to said link, a radius arm pivoted on a fixed axis to which arm the forward end of said driving link is pivoted, a transmitting thrust link pivoted to the radius arm, means for swinging the driving link about its pivotal connection with the radius arm to engage said toothed means with the driver, a connection between the transmitting link and the type bar and means arranged to be engaged by the trailing end of the driving link to control said link to disengage said toothed means from the driver.

47. A writing machine having, in combination,

a continuously rotated toothed power drive member, a series of type bars, mechanism for actuating each of said type bars comprising a driving thrust link, a projection carried by said link for engaging the teeth of the drive member, a transmitting thrust link connected with said first

thrust link, a connection between the transmitting link and a type bar and means positioned to be engaged by the trailing end of the driving link for disengaging the projection carried thereby from the drive member.

OSCAR J. SUNDSTRAND.

CERTIFICATE OF CORRECTION.

Patent No. 2,239,023.

April 22, 1941.

OSCAR J. SUNDSTRAND.

It is hereby certified that error appears in the printed specification of the above numbered patent requiring correction as follows: Page 9, first column, line 12, claim 12, for the word "receive" read --relieve--; page 12, first column, line 32, claim 39, for "ends" read --end--; and that the said Letters Patent should be read with this correction therein that the same may conform to the record of the case in the Patent Office.

Signed and sealed this 10th day of June, A. D. 1941.

(Seal)

Henry Van Arsdale,
Acting Commissioner of Patents.
